UNITED STATES PATENT OFFICE.

ELOISE FOSTER ELLIOT, OF SAN ANTONIO, TEXAS, ASSIGNOR OF ONE-HALF TO MARY FOSTER WHITTLESEY, OF NEW LONDON, CONNECTICUT.

SHOE-SECURING DEVICE.

1,344,996.

Specification of Letters Patent. Patented June 29, 1920.

Application filed August 1, 1919. Serial No. 314,716.

To all whom it may concern:

Be it known that I, ELOISE FOSTER ELLIOT, a citizen of the United States of America, residing at San Antonio, Texas, have invented a new and useful Shoe-Securing Device, of which the following is a specification.

My invention relates particularly to a device or attachment to be used to prevent a small child or baby from accidentally or intentionally pulling off its shoes or ties. Babies' shoes frequently accidentally become unbuttoned or unlaced as the case may be, and are kicked off, or sometimes a child will intentionally unbutton or unlace its shoes to remove them. My invention contemplates the use of a special strap or fastening device, passing around the upper part of the shoe, secured to it near the front and near the rear and having its ends connected together near the back of the shoe where the connecting device is inconspicuous and relatively inaccessible.

Figure 1 is a perspective view of the right shoe of the button type with my improvement applied.

Fig. 2 is a perspective view of the attachment of Fig. 1.

Fig. 3 shows the same attachment spread out flat.

Fig. 4 is a perspective view of the left shoe of the tie type buttoning on the side and with my improvement applied.

Fig. 5 is a perspective view of the attachment of Fig. 4 by itself.

Fig. 6 is a view of the latter attachment spread out flat.

Fig. 7 is a perspective view of the left shoe of the tie type buttoning in front, and with my invention applied.

Fig. 8 is a perspective view of the attachment of Fig. 7.

Fig. 9 is a view of the same attachment spread out flat.

Fig. 10 is a perspective view of the upper part of the right shoe of the laced type, with my improvement attached.

Fig. 11 is a perspective view of the attachment of Fig. 10.

Fig. 12 is a view of the same attachment spread out flat.

In the form shown in Figs. 1, 2 and 3, the upper part of the shoe 15 is surrounded by

the attachment 16 which is secured to it near the front by a suitable attaching device such as the fastener 17, and near the rear by a suitable attaching device such as the fastener 18. The attachment is provided with buttonhole 19 for receiving the upper button 20 of the shoe and thus affording additional means of connection with the shoe and additional means for preventing the shoe from being accidentally or intentionally unbuttoned. Another button 21 is carried by the attachment 16 near its rear and over this the movable end of the attaching device with its buttonhole 22 is adapted to engage so as to secure the two ends of the device together near the point where the fastener 18 is located. This button 21 being at the rear of the shoe is relatively inaccessible and is not subject to accidental unbuttoning by the same movements that would tend to unbutton the usual buttons at the front or side of the shoe. To remove the shoe it is necessary to unbutton the attaching device at the rear and from the button 20 whereupon the shoe may be unbuttoned in the usual way. The securing of the device is effected in the reverse order. That is, the shoe first buttoned up and then the attaching device is fastened over the button 20 and then at the rear.

In the form shown in Fig. 4, the shoe 23 is of the tie type buttoning at the side and the attaching device 24 is cut on an arc so as to conform to the shape of the upper part of the tie. In both forms thus far described, the attaching device is provided with a fastener 17 near the center and a second fastener 18 at one end. The other end of the attachment is provided with a buttonhole 22 and another buttonhole 19 is located so as to correspond with the location of the button 20 on the shoe. The button 21 is provided on the attachment to receive the buttonhole 22.

In the form shown in Figs. 7, 8 and 9, the shoe 25 is of the tie type buttoning in front with a button 20^a. The attachment 26 is provided with a fastener 18 to secure it to the upper part of the shoe near the rear and with a button 21 and buttonhole 22 for connecting the ends of the attachment together near the rear of the shoe. The buttonhole 19^a near the center receives the button 20^a.

of the shoe for securing the front portion of the attaching device to the shoe. This form of attachment is secured permanently to the shoe at only one point and that near the 5 rear.

In the form shown in Figs. 10, 11 and 12, the shoe 27 is of the lace type and the attaching device 28 is secured to the upper edge near the rear by a fastener 18 as in the 10 other forms. The central part of the attaching device is secured to the shoe by a fastener such as 17. The attaching device is provided with a button 21 and a buttonhole 22, as in the other forms of devices, for connecting the ends of the attachment together at or 15 near the rear of the shoe.

It will be noted that in all four forms one 20 end of the attaching device is secured permanently to the shoe at the upper edge near the rear and the opposite end of the attaching device is provided with a buttonhole to coact with a button near the first mentioned end of the device. In the three forms shown in Figs. 1, 4 and 10, there is an additional 25 fastener for permanently securing the attachment to the shoe at a point near the front. In the three forms shown in Figs. 1, 4 and 7, the attaching device is provided with a buttonhole enabling it to be secured 30 to an ordinary button on the shoe so as to prevent the button from being accidentally unbuttoned.

The attachment will be seen to be of a 35 simple and inexpensive character which can be attached at the factory and sold with the shoe, or which can be sold separately and attached easily by anyone. In any event, it serves to supplement and reinforce the usual 40 fastening means of the shoe and thus make it more secure, at the same time rendering

the intentional removal of the shoe by a child more difficult or impossible.

I claim:

1. The combination with a shoe having fastening buttons, of an attaching device 45 comprising a strap having one end secured to the shoe near the rear of the shoe and having a button hole for receiving one of the fastening buttons of the shoe and means for detachably connecting the ends of the strap 50 together.

2. The combination with a shoe, of an attaching strap having one end secured thereto near the rear and having a button near the rear and two buttonholes, one buttonhole being adapted to receive said button and the other buttonhole to receive a button on the 55 shoe.

3. A securing device for a shoe comprising a strap having a fastener at one end for securing it near the rear of a shoe, a button located near said fastener and a buttonhole at the opposite end to coact with said button, and means intermediate the ends for securing 60 the device near the front of the shoe. 65

4. A shoe securing device comprising a strap having means for securing one end to the shoe near the rear, and means for detachably securing the opposite end of the first mentioned end and having a buttonhole 70 near its central portion for receiving the button of a shoe.

5. A shoe securing device comprising a strap having a fastener at one end and a buttonhole at the opposite end, a button near 75 the first mentioned end, a second fastener near the center and a second buttonhole near the central portion.

ELOISE FOSTER ELLIOT.
